UNITED STATES PATENT OFFICE.

GEORGE W. YANSS, OF BRIDGEPORT, CONNECTICUT, ASSIGNOR TO AMERICAN CHAIN COMPANY, INC., A CORPORATION OF NEW YORK.

REAR-FENDER GUARD.

Application filed December 1, 1926. Serial No. 151,931.

This invention relates to fender guards, and more particularly to the type having separate units on each side of the rear of the car.

5 The object is to provide a guard for small popular cars which is easy to install and inexpensive to manufacture. A clear conception of the objects and formation of the invention may be had from the following 10 specification in conjunction with the accompanying drawings, in which

Fig. 1 is a plan view of the fender guard.

Fig. 2 is a front elevation of Fig. 1.

15 Fig. 3 is a cross-section through 3-3 of Fig. 2.

Fig. 4 is a cross-section through 4-4 of Fig. 1.

Fig. 5 is a cross-section through 5-5 of Fig. 1.

20 Fig. 6 is a cross-section through 6-6, of Fig. 1.

Fig. 7 is a modified form of the center portion of Fig. 2.

The now preferred form of the invention 25 as shown in Fig. 1 is for use on Fords, or other cars of a similar design. The numeral 1 designates the guard or bumper units which consist of an impact member, comprising two arc-shaped flat steel bars 2 and 3, vertically spaced and aligned, having eyes in the extremities thereof and a rear bar 4 of flat spring steel, also having eyes in the ends thereof. These eyes are vertically aligned and connected by means of a rivet 35 5, as shown in detail in Fig. 3.

The impact member formed by bars 2 and 3 is vertically aligned and spaced in its center portion by means of a clamp 6, which is shown in detail in Fig. 4. The clamping 40 member 6 consists of a stamped metal piece, having notches 26 in its back to receive bars 2 and 3, and a clamping member 7, having a hole therein to accommodate bolt 8, which holds the bars 2 and 3 in a fixed spaced relation.

45 Each unit 1 is fastened to an L-shaped channel bar 9, by means of bolts 10, and between the bars 9 extends a flat metal cross piece 11, consisting of two pieces and bolted in the center to an angle bracket 12, and on each end to the bars 9.

50 Passing through bracket 12 is a U-bolt 13, so formed that it may pass around the column C of the tire carrier, usually supplied 55 on touring cars of the Ford type.

At the other end of each channel bar 9 from the unit 1, is mounted an angle bracket 14, as shown in Fig. 6, by means of a bolt 15. The angle bracket 14 has a hole therein of the correct diameter to accommodate a body bolt 16, which is provided in this type of car to fasten the extreme end of the usual transverse channel bar 36 to the body.

Midway on bar 9, between the bumper unit 1 and the angle bracket 14, is a series of holes 30 through either of which a bolt 20 is passed for connecting to the bar 9 a strap 18 extending to the usual bracket 39 of the mud guard 38.

70 The connecting plate 19 shown in Fig. 7 is a modified form of connecting means to be used on cars of the Ford coupé and roadster types which have a circular body plate C' to support the post c for the usual tire carrier, 75 the plate C' being secured to the body 37 by bolts c'. The bolt holes 21 in the plate 19 are slotted to fit the bolts c' and aid in supporting the fender guard from said tire carrier structure, the plate 19 being bolted 80 to the cross-piece 11 by bolts 22.

75 When the fender is mounted on the car, as shown in Fig. 1, it affords protection to the rear mud guard and to some extent to the spare tire. This type of fender guard 85 is very simple to install as it is not necessary to drill holes for any of the connecting means as they connect with holes and bolts already provided in the car.

I claim:

90 1. A fender guard for automobiles of the type described, said fender guard having two impact units with a suitable space between them for a tire carrier, means for supporting said guard on said tire carrier, and means 95 for attaching said guard to the frame and fender structure of the automobile by the use of the equipment already existing in automobiles of said type.

100 2. In a fender guard for automobiles of the type described, a pair of impact units each comprising two arcuate bars of strip steel having eyes at the ends thereof, a rear bar having eyes in the ends thereof, bolts for aligning and holding said eyes in vertical alignment, said impact units being spaced apart to accommodate a tire carrier; a pair of mounting bars of an angle shape in cross-section, one of said bars being attached to each of said impact units and a cross bar 105 110

between and connecting said mounting bars for strengthening said guard; and means for fastening said mounting bars to the body and mud guards of the car.

5. 3. In a fender guard for automobiles of the type described, a pair of impact units each comprising two arcuate bars of thin strip steel having eyes in the ends thereof and bolts for aligning and holding said 10 eyes in vertical alignment, said impact units being spaced apart to accommodate a tire carrier; a pair of mounting bars of angle shape in cross section, one of said mounting bars being attached to each of said impact 15 units, and a cross bar between said mounting bars, having means thereon for cooperation with said tire carrier.

4. In a guard for automobiles of the type described, having a tire carrier, a pair of impact units spaced apart to accommodate said tire carrier, a pair of mounting bars, one of said mounting bars being attached to each of said impact units; a cross bar between said mounting bars, and means to connect 25 said cross bar with said tire carrier, said means comprising an angular plate upon said cross bar with a U-shape bolt to engage said tire carrier.

5. In a fender guard for automobiles of the type described having a tire carrier, a pair of impact units spaced apart to accom-

modate said tire carrier, a pair of mounting bars, one of said mounting bars being attached to each of said impact units and a cross bar between said mounting bars, said 35 cross bar having a plate riveted thereto and provided with slotted holes for co-operation with the bolts used to attach said tire carrier to the body of said automobile.

6. A fender guard for automobiles of the type described, said guard comprising a pair 40 of impact units each comprising two arcuate bars of thin strip steel having eyes in the ends thereof, a rear bar of flat spring steel having eyes in the ends thereof, bolts for aligning and holding said eyes in vertical alignment, a pair of bars of angle shape in cross section one of said bars being attached to each of said impact units, a cross bar between said mounting bars for strengthening said guard, means for securing said mounting bars to the body and mud guards of said automobile; a clamping and spacing means for each of said impact units, comprising a front plate having notches in the back 45 thereof to receive said impact bars, and said clamp having a rear plate with a bolt 50 for holding said front and rear plates embracing said bars in close relation.

In testimony whereof, I have signed this specification.

GEORGE W. YANSS.
